DENTAL SYRINGE

Richard B. Cocherell, 85 N. Marengo St., Pasadena, Calif., and James B. Pamplin, 11612 Morgan Lane, Garden Grove, Calif.

Filed Dec. 9, 1963, Ser. No. 77,720

Term of patent 14 years

(Cl. D24—1)

FIGURE 1 is a perspective view of a dental syringe, showing our new design;

FIGURE 2 is a side elevation thereof;

FIGURE 3 is a front elevational view; and

FIGURE 4 is a top plan view thereof.

The dominant features of our design reside in the full line portions.

The fragmentary hose member disclosed in broken lines is for illustrative purposes only.

We claim:

The ornamental design for a dental syringe, substantially as shown and described.
